UNITED STATES PATENT OFFICE

ROBERT S. PEELE, OF HOLLIS, NEW YORK, ASSIGNOR TO THE PEELE COMPANY, OF BROOKLYN, NEW YORK, A CORPORATION OF NEW YORK

OPERATOR FOR ELEVATOR GATES

Application filed May 26, 1931. Serial No. 540,131.

My invention relates to operators for elevator gates, and more particularly to operators for gates upon elevator cars which are operated in conjunction with doors closing the door opening of an elevator shaft.

It is a common practice in warehouses to employ elevator cars, the platform dimensions of which are sufficiently large to receive one or more large vehicles, such as motor or 10 horse drawn trucks, for the purpose of conveying the loaded vehicles from floor to floor in a building, and permitting a single handling of the goods when delivering or removing same to, or from, the warehouse.

It is also a common practice to provide the elevator shafts in such warehouses with door openings in opposite walls, each opening being closed by independently operable doors, and the elevator car being provided, at opposite ends thereof, with gates so as to minimize likelihood of accident during the movement of the car. The elevator car controls are located adjacent one end of the car platform, and with manually operative gates and 25 doors, the efficiency of the elevator equipment is reduced if the operator is required to travel from one end of the car to the other, or the expense of operation of the elevator is increased in the event that two men are employed to operate the car.

The main purpose of my present invention is to provide an electric motor actuated operator for imparting opening and closing movement to the gate as well as to the doors, so 35 that when it is desired to apply opening or closing power to any door, opening or closing power will be simultaneously applied to the gate.

While the circuits to the motors for operating the doors and the gates are controlled by a single penthouse switch, the application of power to the motors for opening the door is controlled by a shaft switch operated by a shoe upon an elevator car so as to limit the application of power to motors operative upon the door closing an opening at which the elevator car is situated at the time that the penthouse switch is closed by a remote control, such as a manually operative switch in the car 45 itself. In that type of elevator where an at-

tendant is not required upon the car, similar manually operative switches are provided at the different landings, such switches being known as floor or hall switches.

The operator of the invention, as shown in the drawings, is applied to a counterbalanced elevator door consisting of two sections oppositely movable in the same vertical plane, each of these sections being of substantially the same weight as the other, and the two sections being connected by a flexible connection passing over a sheave at each side of the door, each sheave forming a part of the operator mechanism and being geared directly to a small individual motor.

The gate, however, is carried by and movable with the car, and the motor for operating the same also has movement with the car. With this construction, it is impossible to place the motor acting upon the gate under the control of shaft switches at different floors, because of the difficulties electrically, and the undesirability of providing separate wiring systems of the doors and for the gate.

While with an operator embodying the invention, the movement of the door sections and the elevator gate is simultaneous, the gate must have substantially twice the movement of either door section, thus necessitating the continued application of power to both the door motors and the gate motor for an interval sufficient to ensure the complete opening or closing movement of the gate. This is compensated for by slippage between the flexible door connections and the sheave operative thereon.

This condition also permits the use of a single limit switch carried by the car and co-operating with a shoe carried by the gate for the purpose of interrupting the application of power, not only to the motor operative upon the gate, but to the motors operative upon the door.

The invention consists primarily in an operator for elevator gates embodying therein the combination with an elevator car, a cam carried thereby, a counterbalanced elevator door mounted in an elevator shaft, flexible connections between the sections of said door, electric motor actuated sheaves

over which said connections pass respectively, and a vertically slideable gate mounted upon the elevator car, of electric conductor lines passing vertically through the shaft, electro-
 5 magnetic pole changing switches controlling the circuit to said conductor lines, a remote manually operative switch mechanism for actuating said magnetic switches, branch lines leading from said shaft conductor lines to the motors of said motor actuated sheaves, a shaft switch adapted to be actuated by a cam upon an elevator car controlling the circuit to said branch lines, an electric motor actuated sheave operative upon said gate, and branch lines extending from said shaft lines, movable with the elevator car and connected with the motor of said last named motor actuated sheave, whereby with the actuation of said pole changing switch mechanism, power may be selectively applied to any door in the elevator shaft, and be simultaneously applied to the motor actuated sheave operative upon said gate; and in such other novel features of construction and 20 combination of parts as are hereinafter set forth and described, and more particularly pointed out in the claims hereto appended.

Referring to the drawings,

Fig. 1 is a view illustrating, in elevation, 30 an embodiment of the invention;

Fig. 2 is a section on the line 2—2 of Fig. 1;

Fig. 3 is a section on the line 3—3 of Fig. 2 upon a larger scale; and

Fig. 4 is a diagrammatic showing of the 35 electrical conditions in the operator.

Like numerals refer to like parts throughout the several views.

In the embodiment of the invention shown in the drawings, the platform of an elevator 40 car is shown at 10, and one of the side walls of said car at 11. A door opening in an elevator shaft having lintel 12, sill 13 and jambs 14 is shown in Figs. 2 and 3 of the drawings. Closing this opening is a counterbalanced door of the usual construction, 45 having an upper section 15 and a lower section 16 mounted upon a vertically extending guide or track structure 17.

Mounted upon this guide or track structure 50 is a fitting 18, having mounted therein a small electric motor 19 and a sheave 20, one shroud 21 of which is in the form of a spur gear enmeshed with a small gear 22 upon the motor shaft. This motor driven sheave mechanism is duplicated upon opposite sides of the doors, and the flexible connections 23 connecting the opposite sides of the door sections 15 and 16 pass about these sheaves. It is to be noted that the use of 55 the sheave affords slippage between same and the flexible connections 23, the purpose of which will more fully appear hereinafter.

Carried by each guide rail structure adjacent the sill 13 is a truck bar stop 24 adapted 60 to engage the truck bar of the lower door sec-

tion, when this bar is substantially flush with the sill 13, and arrest further movement of both of the door sections 15 and 16.

The construction heretofore described, has been used by me prior to the present invention, and it is not my intention to claim same herein, except as a part of a combination in conjunction with the elevator car gate and the means for opening and closing same.

When counterbalanced elevator doors of the type above referred to are used in connection with freight elevators, it is desirable, and sometimes required, to close one or both ends of the elevator car platform 10 by means of a gate. My present invention has to do more particularly with the mechanisms by which such a gate may be opened or closed, the same control mechanism being employed for both the elevator door and the gate, and being so arranged that while opening or closing power may be selectively applied to any door in a shaft, the gate will be opened or closed together with the opening or closing of any selected door.

The gate mechanism in detail will now be described. It consists of a guide or track structure 25, supported from the platform 10 and each side wall 11 adjacent one or each end of the elevator car. Slidably mounted upon such guide or track structures is a vertically sliding gate 26 consisting of an angle metal frame 27, the opening of which is closed by wire mesh suitably braced in any desired manner. Each guide structure is composed of a Z-bar 28 carrying an angle metal bar 29. The Z-bar 28 is riveted or welded to the side wall 11 and extends upwardly beyond the said side wall and the upper end of the angle bar 29. The side bars of the angle metal frame 27 carry an angle bar 30, one flange of which projects between, and is guided by, spaced flanges of Z-bar 28 and the angle bar 29, as shown more particularly in Fig. 3.

Adjacent the top of the side bars of the gate frame 27 are angle brackets 31 by which the supporting chains 32 for the gates are attached to the gate.

The gate 26 may be of any desired height, but it is obvious that whatever its height, it must have a vertical movement substantially equalling the height of the door opening, which movement is twice that required of either door section 15 or 16. It is for this reason that the Z-bar 28 is extended well above the top of the car, since with the opening movement of the gate, the bottom rail of the frame 27 is brought substantially flush with the top of a car.

Carried by the Z-bar 28 adjacent the top thereof is a fitting 33, having mounted therein a small motor 34 and a sheave 35, one shroud 36 of which is in the form of a spur gear enmeshed with a gear 37 upon the motor shaft.

The chain 32 at one side of the door passes over the motorized sheave 35 and is connected with a counterweight 38 slidably mounted in a weight housing 39 suitably braced from the outside of the adjacent side wall 11 of the elevator car.

With the gate 26, only one motorized sheave is required, and consequently the other flexible connection 32 is passed over an idle sheave 40 mounted upon the other guide or track structure 25, and is connected with a counterweight 41 slidably in a housing 42 suitably braced from the outside of the opposite side wall 11 of the car.

By this arrangement of parts, it will be noted, no moving parts of the operator are exposed within the car so as to be endangered by vehicles passing between the car and a floor. The weights and their housings and the chain 32 when the gate is open are protected by the side walls 11, and the motorized sheaves are positioned well above the top of the car.

It will be noted that while the axis of the motorized door sheaves 20 extend at right angles to the wall of the elevator shaft, that the axis of the motorized gate sheave 35 and of the idle sheave 40 extend at right angles to the wall of the shaft in a manner to permit a proper locating of the weight housings while bringing the motor and its sheave close to the side wall 11.

The space available for the motor 34, sheaves 35 and 40, the counterweights 38 and 41 and the housings 39 and 42, is very limited requiring the detailed structural characteristics and arrangement of these parts above referred to.

Located in the penthouse, or in any other desired accessible position, is a switch panel carrying an opening magnetic switch mechanism 43, and a closing magnetic switch mechanism 44. Electrical mains are shown at 45, 46 and 47 and are connected by branch lines 48, 49 and 50 with fixed contacts 51, 52 and 53 of the opening switch mechanism. The movable contacts 54, 55 and 56 of this mechanism are in electrical connection with the conductors 57, 58 and 59 of the shaft conductor line. Leading from the conductor 59 to each of the motors 19 is a branch line 60.

Arranged in the shaft is a shaft switch 61 adapted to be actuated by a shoe or cam 62 carried by and movable with the car. This shaft switch has two pairs of fixed contacts, one contact of one pair being connected by the lead 63 with the conductor 57 of the shaft line, and a contact of the other pair being connected by the line 64 with the conductor 58. The other contact of one of said pairs is connected by the lead 65 with one motor terminal, while the remaining contact of the other pair is connected by the lead 66 with the remaining motor contact. The three contacts of the motor 34 are connected by branch

lines 67, 68 and 69 with the conductors 59, 57 and 58 respectively.

Each of the motors 19 and 34 is a specially constructed three-phase inductive motor having a rotating field so as to permit the reversal of the direction of rotation of the motor by a reversing of two of the three phases of the current source.

It will be noted that while the circuits to each motor 19 are controlled by the switch 61, that the circuits to the motor 34 are controlled solely by either the opening switch 43 or the closing switch 44. This arrangement permits the selective application of power to the motors operative upon any door of the shaft, but assures the operation of the gate irrespective of the operation of any selected door. At the same time, the application of power to the motors at any door will result in the simultaneous application to the motor of the gate, whether the power be applied for the purpose of opening or closing the doors, and that the gate will have movement in the same direction as the upper door section of the door.

The fixed contacts 70, 71 and 72 are in direct electrical connection with the mains 45, 46 and 47, and the movable contacts 73, 74 and 75 of said switch mechanism are in electrical connection through the leads 76, 77 and 78 with the shaft conductors 58, 57 and 59 respectively. By this arrangement, the closing of the switch 44 will place the mains 45 and 46 in electrical connection with the conductors 58 and 57 respectively, while the closing of the switch 43 will place the mains 45 and 46 in electrical connection with the conductors 57 and 58. This shifting of the lines 57 and 58 will have the same operative effect as to each of the motors 19 and 34.

Carried by, and movable with, the car is a switch mechanism 79 having a manually operative opening switch 80, one of the fixed contacts of which is connected by the lead 81 with one of the fixed contacts of the limit switch 82, the other fixed contact of said circuit switch being connected by the lead 83 with one terminal of the winding of the magnet of the switch 43, the other terminal of which magnet is connected by the leads 84, 85 and 48 with the main 45. The other fixed contact of the opening switch 80 is connected by the leads 86 and 50 with the main 47.

Also included in the switch 79 is a manually operative closing switch 87, one fixed contact of which is connected with the lead 86, and the other fixed contact of which is connected by the lead 88 with one terminal of the winding of the magnet of the closing switch 44, the other terminal of which winding is connected through the leads 85 and 48 with the main 45.

Each of the switches 43 and 44 is normally open, while the limit switch 82 is normally closed.

63 The limit switch 82 is mounted upon the guide or track structure 25 adjacent the motorized sheave 35, and therefore is movable with the car so as to be operative as to any door in a shaft as well as to the gate.

64 Carried by one of the angle brackets 31 is a cam 89 positioned adjacent the top of the gate in a position where it will engage and actuate the limit switch substantially simultaneously with the completion of the upward or opening movement of the gate.

65 The operation of the herein described mechanism is substantially as follows:—

66 Normally, all of the doors in an elevator shaft are closed, and the gate 26 is also closed. This condition continues so long as the elevator car is having movement. When a car is stopped at any floor in a shaft, the cam or shoe 62, shown conventionally in Fig. 4, is in 70 the operative relation to the shaft switch 61 so that said switch is, or may be, closed so as to place the motors 19 in electrical connection with the shaft conductors 57 and 58, the conductor 59 being in direct electrical connection 75 with said motors at all times.

67 The cam 62 may be either a fixed cam or a receding cam, as desired, since the closing of the switch 61, of itself, will not result in the application of power to said motors 20.

68 With the switch 61 closed, opening power may be applied to that door adjacent which the car is at rest, by closing the opening switch 80. The closing of this switch closes the circuit from the lines 45 and 47, which circuit includes the winding of the magnetic switch 43 and the contacts of the limit switch 82. The energizing of the magnet 43 actuates the movable contacts 54, 55 and 56 so as to close the circuit to the shaft conductors 57, 58 and 59 thus energizing the motors 19, and the motor 34. There is a continued application of power to each of said motors until the gate 26 has completed its full opening movement.

69 As heretofore pointed out, the duration of the run of the motors 19, necessary to effect a full opening movement of the counterbalanced elevator door, is only approximately one-half of that required to effect a full opening movement of the gate 26. Nevertheless, the magnetic switch mechanism 43 must be held closed until the gate has attained its full opening movement, or for a sufficient interval to permit the development of moving inertia of the door sections and of the gate to complete the opening movement.

70 By using the limit switch 82 in the circuit controlled by the opening switch 80, for energizing the winding of the magnetic switch 43, this circuit will be automatically interrupted when the gate 26 has reached its full open position, thus de-energizing the magnet 43 and permitting the automatic opening of the circuit to the shaft conductors 57, 58 and 59. 75

71 In this manner, the application of power to

72 the motors 19 is controlled by the movement of the gate 26 during the opening movement of the door and of the gate. Consequently, power is applied to the motors 19 for an interval in excess of that required to fully open the elevator door, the motors 19 running idly following the complete opening movement of said door. The chains or other flexible connections 23 have no movement, while the motors 19 are thus running idly, slippage 75 occurring between said connections and said motors to permit the mode of operation above described.

76 The above mode of operation is made possible because of the engagement of the truck bar of the lower door section 16 with the truck bar stop 24, since when the lower door section comes to rest, the connections 23 are relieved from the load of this section, which load is essential to ensure the movement of the doors by the sheaves 20. With a door operator of the type herein described, the traction between the sheaves 20 and the connections 23 is developed as a result of the substantially balanced loads upon opposite 90 ends of said connections, the door sections 15 and 16.

77 When it is desired to close the door and the gate, it is merely necessary for the attendant to close the switch 87, thus energizing the winding of the magnet 44 and actuating the movable contacts 73, 74 and 75 in a way to apply potential to the shaft lines 57, 58 and 59 reversing the polarity of the lines 57 and 58 in a manner to impart a reverse rotation to the motors 19 and 34. The circuit controlled by the switch 87 does not include a limit switch, but the application of potential to the motors 19 is possible only as a result of the closing of the switch 61.

78 It will be noted that the motor 34 may be energized entirely independently of the switch 61, either to open or close the gate.

79 The free running of one chain 32 over the motor actuated sheave 35 permits the control of the movement of the gate in a manner to avoid possible injury to anyone positioned below the gate. In fact, movement of the gate in either direction may be readily restrained by merely grasping the gate, and this may be done without subjecting the motor to the likelihood of damage thereto.

80 In the construction shown, both the elevator door and the gate may be manually actuated in the event of failure of the motive power for the motors 19 and 34.

81 The conductors 67, 68 and 69, as well as the connections 83, 86 and 88, are contained in a cable having movement with the car.

82 As heretofore pointed out, the motor 34, the chains 32, the counterbalancing weight and the weight boxes are all positioned outside of the side wall 11 of the elevator car so as not to be subjected to likelihood of

breakage or disarrangement by vehicles passing to and from the elevator car. These various parts are located on one side of the car only, and occupy but a few inches of space.

The construction described ensures the simultaneous application of power to both the doors and the gate through a single manually operative switch mechanism, thus precluding possibility of the failure of the attendant to properly actuate both of these safeguards.

If an attendant should manually open or close either the doors or the gates, power may nevertheless be applied to the other for the purpose of opening or closing it.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. An operator for elevator gates embodying therein the combination with an elevator car, a cam carried thereby, a counterbalanced elevator door mounted in an elevator shaft, flexible connections between the sections of said door, electric motor actuated sheaves over which said connections pass respectively, and a vertically slidable gate mounted upon the elevator car, of electric conductor lines passing vertically through the shaft, electro-magnetic pole changing switches controlling the circuit to said conductor lines, a remote manually operative switch mechanism for actuating said magnetic switches, branch lines leading from said shaft conductor lines to the motors of said motor actuated sheaves, a shaft switch adapted to be actuated by a cam upon an elevator car controlling the circuits to said branch lines, an electric motor actuated sheave operative upon said gate, and branch lines extending from said shaft lines, movable with the elevator car and connected with the motor of said last named motor actuated sheave, whereby with the actuation of said pole changing switch mechanism, power may be selectively applied to any door in the elevator shaft, and be simultaneously applied to the motor actuated sheave operative upon said gate.

2. An operator for elevator gates embodying therein the combination with an elevator car, a cam carried thereby, a counterbalanced elevator door mounted in an elevator shaft, flexible connections between the sections of said door, electric motor actuated sheaves over which said connections pass respectively, and a vertically slidable gate mounted upon the elevator car, of electric conductor lines passing vertically through the shaft, electro-magnetic pole changing switches controlling the circuit to said conductor lines, a remote manually operative switch mechanism for actuating said magnetic switches, branch lines leading from said shaft conductor lines to the motors of said motor actuated sheaves, a shaft switch adapted to be actuated by a cam upon an elevator car controlling the circuits to said branch lines, an electric motor actuated sheave operative upon said gate, and branch lines extending from said shaft lines, movable with the elevator car and connected with the motor of said last named motor actuated sheave, whereby with the actuation of said pole changing switch mechanism, power may be selectively applied to any door in the elevator shaft, and be simultaneously applied to the motor actuated sheave operative upon said gate.

3. An operator for elevator gates embodying therein the combination with an elevator car, a cam carried thereby, a counterbalanced elevator door mounted in an elevator shaft, flexible connections between the sections of said door, electric motor actuated sheaves over which said connections pass respectively, and a vertically slidable gate mounted upon the elevator car, of electric conductor lines passing vertically through the shaft, electro-magnetic pole changing switches controlling the circuit to said conductor lines, a remote manually operative switch mechanism for actuating said magnetic switches, branch lines leading from said shaft conductor lines to the motors of said motor actuated sheaves, a shaft switch adapted to be actuated by a cam upon an elevator car controlling the circuits to said branch lines, an electric motor actuated sheave operative upon said gate, and branch lines extending from said shaft lines, movable with the elevator car and connected with the motor of said last named motor actuated sheave, whereby with the actuation of said pole changing switch mechanism, power may be selectively applied to any door in the elevator shaft, and be simultaneously applied to the motor actuated sheave operative upon said gate.

4. An operator for elevator gates embodying therein the combination with an elevator car, a cam carried thereby, a counterbalanced elevator door mounted in an elevator shaft, flexible connections between the sections of said door, electric motor actuated sheaves over which said connections pass respectively, and a vertically slidable gate mounted upon the elevator car, of electric conductor lines passing vertically through the shaft, electro-

magnetic pole changing switches controlling the circuit to said conductor lines, a remote control for said pole changing switches including a manually operative opening switch, a normally closed limit switch, and electrical

70

conductors from a source including the winding of one of said magnetic switches, said limit switch and said manually operative switch, branch lines leading from said shaft conductor lines to the motors of said motor actuated sheaves, a shaft switch adapted to be actuated by a cam upon an elevator car controlling the circuits to said branch lines, an

75

electric motor actuated sheave operative upon said gate, branch lines extending from said shaft lines, movable with the elevator car and connected with the motor of said last named motor actuated sheave, whereby with the actuation of said pole changing switch mechanism, power may be selectively applied to any door in the elevator shaft, and be simultaneously applied to the motor actuated sheave operative upon said gate, and means carried by said gate co-operating with

80

said limit switch, whereby the circuit to said shaft conductor lines will be automatically interrupted toward the completion of the opening movement of the gate.

85

5. In an operator for elevator gates, the combination with electric motor actuated sheaves operative respectively upon a series of elevator doors in a shaft, of an elevator car, a vertically slidable gate mounted thereon, a motor driven sheave operative upon said gate, electric conductor lines passing vertically through the shaft, a shaft switch whereby the power from said lines may be selectively applied to the motors adjacent any door in the shaft, electrical connections between said lines and said motor driven sheave, whereby said sheave will be actuated simultaneously with the actuation of the motors operative upon any selected door, electro-magnetic pole changing switches controlling the circuit to the conductors of said shaft line, and a remote manually operative switch mechanism for controlling the actuation of said magnetic switches.

90

6. In an operator for elevator gates, the combination with electric motor actuated sheaves operative respectively upon a series of elevator doors in a shaft, of an elevator car, a vertically slidable gate mounted thereon, a motor driven sheave operative upon said gate, electric conductor lines passing vertically through the shaft, a shaft switch whereby the power from said lines may be selectively applied to the motors adjacent any door in the shaft, electrical connections between said lines and said motor driven sheave, whereby said sheave will be actuated simultaneously with the actuation of the motors operative upon any selected door, electro-magnetic pole changing switches controlling the circuit to the conductors of said shaft line, and a remote manually operative switch mechanism for controlling the actuation of said magnetic switches.

100

7. In an operator for elevator gates, the combination with electric motor actuated sheaves operative respectively upon a series of elevator doors in a shaft, of an elevator car, a vertically slidable gate mounted thereon, a motor driven sheave operative upon said gate, electric conductor lines passing vertically through the shaft, a shaft switch whereby the power from said lines may be selectively applied to the motors adjacent any door in the shaft, electrical connections between said lines and said motor driven sheave, whereby said sheave will be actuated simultaneously with the actuation of the motors operative upon any selected door, electro-magnetic pole changing switches controlling the circuit to the conductors of said shaft line, and a remote manually operative switch mechanism for controlling the actuation of said magnetic switches.

110

8. In an operator for elevator gates, the combination with electric motor actuated sheaves operative respectively upon a series of elevator doors in a shaft, of an elevator car, a vertically slidable gate mounted thereon, a motor driven sheave operative upon said gate, electric conductor lines passing vertically through the shaft, a shaft switch whereby the power from said lines may be selectively applied to the motors adjacent any door in the shaft, electrical connections between said lines and said motor driven sheave, whereby said sheave will be actuated simultaneously with the actuation of the motors operative upon any selected door, electro-magnetic pole changing switches controlling the circuit to the conductors of said shaft line, and a remote manually operative switch mechanism for controlling the actuation of said magnetic switches.

120

9. In an operator for elevator gates, the combination with electric motor actuated sheaves operative respectively upon a series of elevator doors in a shaft, of an elevator car, a vertically slidable gate mounted thereon, a motor driven sheave operative upon said gate, electric conductor lines passing vertically through the shaft, a shaft switch whereby the power from said lines may be selectively applied to the motors adjacent any door in the shaft, electrical connections between said lines and said motor driven sheave, whereby said sheave will be actuated simultaneously with the actuation of the motors operative upon any selected door, electro-magnetic pole changing switches controlling the circuit to the conductors of said shaft line, and a remote manually operative switch mechanism for controlling the actuation of said magnetic switches.

125

10. In an operator for elevator gates, the combination with electric motor actuated sheaves operative respectively upon a series of elevator doors in a shaft, of an elevator car, a vertically slidable gate mounted thereon, a motor driven sheave operative upon said gate, electric conductor lines passing vertically through the shaft, electro-magnetic pole changing switches controlling the circuit to the conductors of said shaft line, and a remote manually operative switch mechanism for controlling the actuation of said magnetic switches.

130

shaft line, a remote control for said pole changing switches including a manually operative opening switch, a normally closed limit switch, and electrical conductors from 5 a source including the winding of one of said magnetic switches, said limit switch and said manually operative switch, and means carried by the gate co-operating with said limit switch, whereby the circuit to said shaft conductor lines will be automatically interrupted toward the completion of the opening movement of the gate.

5. An operator for elevator gates embodying therein the combination with an elevator 15 car, a cam carried thereby, a counterbalanced elevator door mounted in an elevator shaft, flexible connections between the sections of said door, electric motor actuated sheaves over which said connections pass respectively, and a vertically slideable gate mounted upon the elevator car, of electric conductor lines passing vertically through the shaft, electro-magnetic pole changing switches controlling the circuit to said conductor lines, a 20 remote manually operative switch mechanism for actuating said magnetic switches, branch lines leading from said shaft conductor lines to the motors of said motor actuated sheaves, a shaft switch adapted to be actuated by a 25 cam upon an elevator car controlling the circuits to said branch lines, means stopping the opening movement of the elevator door, an electric motor actuated sheave operative upon said gate, and branch lines extending 30 from said shaft lines, movable with the elevator car and connected with the motor of said last named motor actuated sheave, whereby with the actuation of said pole changing switch mechanism, power may be 35 selectively applied to any door in the elevator shaft, and be simultaneously applied to the motor actuated sheave operative upon said gate.

6. An operator for elevator gates embodying therein the combination with an elevator car, a cam carried thereby, a counterbalanced elevator door mounted in an elevator shaft, flexible connections between the sections of said door, electric motor actuated sheaves 50 over which said connections pass respectively, means stopping the opening movement of the elevator door, and a vertically slideable gate mounted upon the elevator car, of electric conductor lines passing vertically 55 through the shaft, electro-magnetic pole changing switches controlling the circuit to said conductor lines, a remote control for said pole changing switches including a manually operative opening switch, a normally closed 60 limit switch, and electrical conductors from a source including the winding of one of said magnetic switches, said limit switch and said manually operative switch, branch lines leading from said shaft conductor lines to the 65 motors of said motor actuated sheaves, a

shaft switch adapted to be actuated by a cam upon an elevator car controlling the circuits to said branch lines, an electric motor actuated sheave operative upon said gate, branch lines extending from said shaft lines, movable with the elevator car and connected with the motor of said last named motor actuated sheave, whereby with the actuation of said pole changing switch mechanism, power may be selectively applied to any door in the elevator shaft, and be simultaneously applied to the motor actuated sheave operative upon said gate, and means carried by said gate co-operating with said limit switch, whereby the circuit to said shaft conductor lines will be automatically interrupted toward the completion of the opening movement of the gate.

In witness whereof I have hereunto affixed my signature this 19th day of May, 1931.

ROBERT S. PEELLE.
